UNITED STATES PATENT OFFICE

FRANK C. GREENE, OF CHICAGO, ILLINOIS

BLAST FURNACE

Application filed June 27, 1931. Serial No. 547,385.

This invention relates to an improved blast furnace and, more particularly, to blast furnaces of reduced height and improved operating characteristics.

5 A heretofore usual blast furnace for smelting iron is a stack-like structure having a height in the neighborhood of from 80 to 90 feet, although this height may be varied according to the daily output desired. 10 A charge consisting essentially of iron ore, fuel, and limestone is fed into the top of this stack, the limestone and the fuel, usually coke, being in fairly large pieces. A blast of air is forced upwardly through this 15 charge and the ingredients react with one another and with the air to produce, finally, at the bottom of the furnace, molten iron.

Complex reactions take place in the interior of the blast furnace involving the production of carbon dioxide and carbon monoxide gases, the latter being an important medium in the reduction of the iron oxide ore to the metallic condition. The size and height of the blast furnace make it a costly 25 apparatus to construct, but the prevailing height has been found necessary to give time for the complex reactions, involved in the reduction of the ore, to take place. The coke used as fuel is also more expensive than coal, but bituminous coal has not been generally used due to the necessity of providing a fuel with a strong physical structure which will not crush and compact in the furnace to prevent the free passage and distribution of the air blast through the charge. 30 Also, the air blast is usually supplied to the furnace at a pressure of 30 to 50 pounds and this would have to be materially increased if a fuel which decrepitates and packs in the furnace were used. If the height of the blast furnace could be reduced without reducing the capacity of the furnace, great economies of operation and cost of installation would result. Large savings could also 40 be effected if coke could be replaced by the less expensive bituminous coal.

It has now been discovered that a blast furnace may be constructed of reduced height and in which bituminous coal may 45 be used as a fuel. It is, accordingly, an

object of the invention to provide a blast furnace of reduced height for the same output capacity. Another object of the invention is to provide a blast furnace employing coal as fuel. Still another object of the invention is to provide a blast furnace in which the reaction time of the charge is lessened and in which the air blast pressure is reduced. A further object of the invention is to provide a blast furnace in which an improved porosity of the charge may be maintained. An additional object of the invention is to provide a method of reducing ore to metal in an improved and efficient manner. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:

Fig. 1 is a sectional elevation of a new blast furnace; Fig. 2 is a horizontal section taken along the line 2-2 of Fig. 1; Fig. 3 is an enlarged detail view of a portion of the blast furnace; and Fig. 4 is a fragmentary sectional view taken along the line 4-4 of Fig. 1.

Referring to Fig. 1, it will be noted that the structure there shown has many of the features of the lower part of a standard blast furnace, but that, in place of an open top closed by a bell, the top of the present structure is closed with a crown 3. The structure may be viewed as a standard blast furnace which has been cut off and crowned at a point corresponding to the temperatures prevailing in a blast furnace from 500° to 800° C., although it will be understood that the height of my blast furnace will be determined by the factors met with in each installation. The body of the stack part of the furnace comprises an outer cylindrical wall 4 supported by numerous buck stays 5, and resting on a frame 6, which is suitably

sealed against the escape of gases. Below the wall 4 the furnace narrows to form a bosh 7 as in the standard blast furnace. A hearth 8 rests on foundations 9. A bustle 5 10 supplies a blast of air to the tuyères 11 through which the air passes into the furnace. Within the body of the furnace above the bosh is provided a cylindrical casing 12 concentrically spaced from the inner surface 10 13 of the furnace wall 4. Between this casing and the inner surface of the wall is also concentrically spaced a cylindrical muffle 14 which is curved inwardly at its upper extremity 15 toward the interior of the furnace. This muffle is adapted to be rotated by means described below. Inside the rotatable muffle is a stationary screw or stator 16 having upon its exterior a number of flights 17 which may be integrally cast or 20 otherwise attached to the exterior of the stator. The number of flights may be varied but six has been found to be a convenient number.

The charge consisting of iron ore, lime- 25 stone, and coal, which have been ground together, is fed to the blast furnace at a point somewhat above the bosh instead of through the top as in standard practice. The charge, as mixed, may be stored in a bin 18 from 30 which it is fed into a hopper 19 where a conveyor 21 picks it up and transports it to the blast furnace. Any well known type of conveyor suitable for the purpose may be used, such as a screw conveyor. The charge 35 is poured into a rotatable feed pan 22 which surrounds the inner casing 12, rotation of the feed pan being from a series of pinions 23 or other suitable driving means which mesh with a bull gear 23' on the outside of 40 the feed pan. The feed pan supports the vertical cylindrical muffle 14 which rotates therewith, the feed pan and the muffle bearing upon flanged roller bearings 24. These latter are set in the furnace brick-work and 45 may be water-cooled. The charge is deflected inside the muffle by a number of stationary vanes 25 which crowd the charge into the stationary flights 17.

The mixed charge fed into the muffle is 50 caused to travel upwardly on the flights 17 of the stator 16 due to the friction between the rotating muffle and the charge. It will be noted that, in the drawing, the space between the muffle 14 and the stator 16 in- 55 creases gradually toward the top allowing for expansion of the charge, which will occur. Both the stator and the muffle may be made in sections, each section having internally turned flanges whereby it can be 60 connected with adjacent sections, but this is for convenience of assembly and other means of constructing these elements may be used as found to be feasible. A slight clearance will be left between the muffle and the stator 65 to allow for expansion.

Between the muffle 14 and the inner surface 13 of the furnace wall is a passage 26 communicating with the interior of the furnace and having an outlet 27 communicating with stoves or with a stack or with other installations according to the disposition which it is desired to make of exit gases from the blast furnace. 70

The operation of the new blast furnace is as follows. A mixed charge of iron ore, slack coal and limestone which has been finely divided, say to pass a hundred mesh screen, is conveyed from the hopper 19 through the conveyor 21 into the rotating feed pan 22 where it is taken up and forced inside the muffle 14 by the vanes 25. The intimately mixed charge is caused to rise on the flights 17 of the stator 16 by frictional contact with the inner surface of the rotating muffle 14, which surface may be left rough as formed, and rises gradually to the top of the furnace under the crown 3 where the inwardly curved extremity of the muffle forces it into the interior of the furnace. While the charge is moving upwardly between the casing 12 and the muffle 14, blast furnace gases leaving the charge within the furnace pass downwardly through the passage 26 between the muffle and the furnace wall 4 where they heat the incoming charge, the gases finally passing out through the gas off-take 27. Heat will also be imparted to the fresh charge from the contents of the furnace through the casing 12. The charge thus receives progressive temperature impressions up to at least 600° C. The turbulent flow of the charge resulting from the frictional contact of the muffle 14 with the material on the flights 17, promotes rapid heat absorption. Free moisture picked up by the materials or remaining after wet grinding of these, is driven off by the heat and may be prevented from passing upward through the mass by adjusting the speed of propulsion so that the charge lags and fills the spaces between the stator and the muffle so as to seal these spaces. The free moisture will consequently pass downward as superheated steam and give up its total heat to the cold incoming mass. After the mass has been dried, the coal therein starts melting at about 350° C., thus becoming plastic and tending to bind the minute neighboring particles of ground limestone and iron ore. A very intimate contact between the fuel and the other ingredients of the charge thus results. By the time the charge has been heated to 450° C. by the heat from the interior of the furnace and the heat from the exit gases, the fuel has set to a form which is many times as reactive as metallurgical coke, i. e., it has many times the ability of metallurgical coke to reduce carbon dioxide to carbon monoxide. The reactivity of the fuel increases 110 115 120 125 130

until a maximum is reached at about 600° C. and, in the preferred method of operating the blast furnace, this is the temperature at which the charge is passed into the interior of the shaft or stack of the furnace.

It will be seen that the charge has been raised during its passage between the muffle and the casing 12, to a temperature which approaches that prevailing in a standard blast furnace at a like distance above the hearth. No air has reached the fuel up to this point and, consequently, any reduction of the ore which may have taken place will be due primarily to the reaction of coal carbon or hydro-carbons with the iron oxide. However, the fuel in the charge has swelled and imparted great porosity to the charge, the coal having bound itself during the plastic stage in intimate contact with the fine particles of iron ore and limestone present. When this highly reactive charge drops into the interior of the furnace, the carbon dioxide there present will be quickly reduced to carbon monoxide by the highly active fuel and, since the fuel is in intimate contact with the particles of ore, the production of carbon monoxide, which is the most important agent in the reduction of the ore, will take place in close proximity to the ore particles. The reduction of the ore will proceed at a rapid rate and the passage of the charge down through the relatively short length of the improved blast furnace will suffice to produce molten metal at the hearth 8 where it may be drawn off through the tap hole 28.

It will be seen from the above that a large part of the height of the blast furnace has been done away with, the same results being obtained with a lower stack; in fact, practically one-half of the ordinary stack may be left off. The function of this portion of the stack which has been omitted is to heat the charge to a reacting temperature and to subject the iron oxide ore to the reducing effect of carbon monoxide and carbon. Complex reactions take place in the stack involving the production and distribution of both carbon monoxide and carbon dioxide accompanied by partial or complete reduction of portions of the charge. The method of operating the present construction must supply an effect upon the charge approximately equivalent to the effect produced in the upper part of the stack of the ordinary blast furnace. The heating effect is achieved in part or in whole by the temperature increments which the fresh charge receives in its passage between the inner casing and the muffle. In addition, by making use of coal instead of coke in the charge and by finely dividing and intimately mixing the constituents of the charge, it is possible to bring the mixture to the highly reactive condition defined above as the ability to reduce carbon

dioxide to carbon monoxide. In this highly porous mass permeable to gas, it is thought that carbon monoxide reaching the charge as it is passed into the interior of the furnace, may be catalyzed by the iron oxide of the ore to produce finely divided carbon which deposits adjacent the particles of ore distributed throughout the mass. Carbon dioxide is also produced as the other product of its reaction, but it is the finely divided carbon which is of present interest. This finely divided carbon, distributed adjacent or in contact with the particles of ore, is extremely reactive and promotes the work of reduction by additional carbon monoxide until the last remnants of iron oxide are reduced rapidly and completely. This application of the known reaction $2CO = C + CO_2$, offers an explanation of the manner in which a blast furnace charge, finely divided and intimately mixed, is brought by the present method to a condition where it quickly approximates the reduced condition obtained in standard blast furnace practice only by passage through a long stack.

By use of the present method and apparatus for reducing ore, low sulphur slack coal may be made to take the place of the more expensive coke. Installation and operating costs may be reduced due to the employment of a smaller structure for the same output of pig iron. In addition, it may be possible to use less blast air and the blast pressure can be materially reduced since the air must be forced through a smaller column of charge and the increased porosity of the charge imparted by the preheating treatment results in increased permeability of the charge to the blast.

While a dry charge may be used, it is also possible to employ wet grinding for mixing the materials for the purpose of reducing dust losses and reducing grinding costs. Excess water may be removed by means of a filter press, but a certain amount of water in the charge is advantageous since, when driven off during the reactivating treatment, it increases the porosity of the mass. Porosity of the mass during the preheating treatment is also increased by the driving off of volatiles and oxygen all of which result in an increased surface upon which reaction may take place. A further advantage of the present method over those now in use is that the porous charge containing its constituents in finely divided form permits carbon monoxide to reach every particle of iron oxide, whereas in the customary practice, reduction of the lump charge requires a high stack and even then reduction is not wholly efficient.

The present method and apparatus, while involving a radical departure in operating technique, achieves ultimate conformation to the chemical reactions of the standard

blast furnace and, consequently, a product of similar characteristics.

While the main product of my blast furnace is naturally pig iron, another product is a fuel gas of higher calorific value than that now obtained from standard blast furnaces. By withdrawing gases from a furnace having a depth of charge approximately equal to that described above, a gas is obtained having a high carbon monoxide content undiluted by increasing amounts of carbon dioxide such as are acquired in the upper region of the standard blast furnace. In effect, removal of the gas takes place at a point corresponding to the so-called "Franchot off-take" in the standard blast furnace where it is known a richer gas may be obtained.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention.

1. A blast furnace comprising a furnace body, a casing concentrically spaced from the inner wall of said furnace body, means for feeding a charge into the lower end of the space defined by said wall and said casing, and means for discharging said charge from the upper end of said space into the interior of the furnace.

2. A blast furnace comprising a furnace body, a casing concentrically spaced from the inner wall of said furnace body, a muffle concentrically spaced between said casing and said inner wall, means for passing a charge upwardly between said casing and said muffle into the interior of said furnace and means for passing furnace gases downwardly between said muffle and said inner wall.

3. A blast furnace comprising a furnace body having the characteristics of a standard blast furnace for smelting iron, cut off and crowned in the temperature zone from 500°-800° C., a casing concentrically spaced from the inside wall of said furnace body, means for passing a charge between said casing and said inner wall, and means for discharging the same into the interior of said furnace.

4. A blast furnace comprising a furnace body having the characteristics of a standard blast furnace for smelting iron, cut off and crowned in the temperature zone from 500° to 800° C., a casing concentrically spaced from the inner wall of said furnace body, a muffle concentrically spaced between said casing and said wall, means for passing a blast furnace charge between said casing and said muffle into the interior of said furnace and means for passing the furnace

gases between said muffle and said wall in heat transfer relation to said charge.

5. A blast furnace comprising a furnace body having the characteristics of a standard blast furnace for smelting iron, cut off and crowned in the temperature zone from 500° to 800° C., a casing concentrically spaced from the inner wall of said furnace body, a muffle concentrically spaced between said casing and said inner wall, means for passing a finely divided blast furnace charge between said casing and said muffle, means for passing the blast furnace gases between said muffle and said wall to heat the charge, and means for discharging the heated charge into the interior of the furnace.

6. A blast furnace comprising a furnace body, a casing concentrically spaced from the inner wall of said furnace body, a rotatable muffle concentrically spaced between said casing and said inner wall and a stationary screw mounted between said muffle and said casing.

7. A blast furnace comprising a furnace body, a casing concentrically spaced from the inner wall of said furnace body, a rotatable muffle concentrically spaced between said casing and said inner wall, a stationary screw mounted between said muffle and said casing, means for feeding a blast furnace charge to said screw and means for discharging the same into the interior of said furnace.

8. A blast furnace comprising a furnace body, a casing concentrically spaced from the inner wall of said furnace body, a rotatable muffle concentrically spaced between said casing and said inner wall, a stationary screw mounted between said muffle and said casing, means for feeding a blast furnace charge to said screw, means for rotating said muffle to lift said charge, and means for discharging the same into the interior of said furnace.

9. A blast furnace comprising a furnace body, a casing concentrically spaced from the inner wall of said furnace body, a rotatable muffle concentrically spaced between said casing and said inner wall, a stationary screw mounted between said muffle and said casing, means for feeding a blast furnace charge to said screw, means for rotating said muffle to lift said charge, and said muffle having an inwardly curved top to direct said charge into the interior of said furnace.

10. A blast furnace comprising a furnace body having the characteristics of a standard blast furnace for smelting iron, cut off and crowned in the temperature zone from 500° to 800° C., a casing concentrically spaced from the inner wall of said furnace body, a rotatable muffle concentrically spaced between said casing and said wall, a stationary screw mounted between said muffle and said casing, means for feeding a blast fur-

nace charge to said screw and means for rotating said muffle to lift said charge and to discharge the same into the interior of said furnace.

5 11. A blast furnace comprising a furnace body having the characteristics of a standard blast furnace for smelting iron, cut off and crowned in the temperature zone from 500° to 800° C., a casing concentrically spaced from the inner wall of said furnace body and a rotatable muffle spaced between said casing and said wall.

10 12. A blast furnace comprising a furnace body, a casing concentrically spaced from the inner wall of said furnace body, a rotatable muffle concentrically spaced between said casing and said wall, a screw mounted between said casing and said muffle, means for feeding a blast furnace charge to said screw, means for rotating said muffle to raise said charge along said screw and into the interior of said furnace, means for passing blast furnace gases counter-currently to said charge and in heat transfer relation therewith, and means for passing said gases out of said furnace.

15 13. A blast furnace comprising a furnace body having the characteristics of a standard blast furnace for smelting iron, cut off and crowned in the temperature zone be-

tween 500° to 800° C., means for continuously passing a blast furnace charge containing coal, counter-currently to hot gases from said blast furnace and means for delivering the heated charge to the interior of said furnace.

20 14. A blast furnace comprising a furnace body having the characteristics of a standard blast furnace for smelting iron, cut off and crowned in the temperature zone between 500° to 800° C., and associated means for heating a blast furnace charge containing coal, so that, upon being discharged into the top of the furnace, it assumes a condition equivalent to a standard charge in a standard blast furnace at the same distance above the hearth.

25 15. A blast furnace comprising a furnace body having the characteristics of a standard blast furnace for smelting iron, cut off and crowned in the temperature zone between 500° and 800° C., and associated means for heating a blast furnace charge containing coal so that, upon being discharged into the top of the furnace, the iron in said charge is reduced to molten metal during its passage through the body of said furnace.

30 Signed by me this 19th day of June, 1931.
FRANK C. GREENE.
